UNITED STATES PATENT OFFICE.

ANTON SCHWITTER, OF BROOKLYN, NEW YORK.

ROSE-ENGINE.

SPECIFICATION forming part of Letters Patent No. 314,064, dated March 17, 1885.

Application filed January 15, 1885. (No model.)

To all whom it may concern:

Be it known that I, ANTON SCHWITTER, a citizen of the United States, residing at Brooklyn, in the county of Kings and State of New York, have invented new and useful Improvements in Rose-Engines, of which the following is a specification.

This invention relates to a rose-engine which produces rectilinear designs or designs composed of right lines, in contradistinction to rose-engines which produce curvilinear designs.

My present invention consists in the combination, with the graver or tool-support, of the pattern-slide, the screw-spindle for imparting to this slide the required motion, the work-support, the carriage supporting the pattern-slide and the work-support, the tracer-slide, a stop which retains the graver out of contact with the work when the tracer is opposite to one of the high portions of the pattern, and means for imparting to the carriage a reciprocating motion, so that by imparting to the carriage, the graver-support, and the pattern-slide the required movements the design contained on the face of the pattern is reproduced upon the face of the work. With the tracer-slide and the carriage is combined a pantograph connection for changing the scale of the reproduced design. The tracer is secured to an arm, which is hinged to the tracer-slide and which bears upon a projection extending from the graver-support, so that the position of the graver in regard to the work is automatically controlled by the action of the tracer upon the pattern.

In the accompanying drawings, Figure 1 represents a sectional front view of my rose-engine, the plane of section being indicated by the line $x\ x$, Fig. 2. Fig. 2 is a longitudinal vertical section in the plane $y\ y$, Fig. 1. Fig. 3 is a horizontal section in the plane $z\ z$, Fig. 1. Fig. 4 is a face view of the pattern on a larger scale than the previous figures. Fig. 5 is a face view of the work produced from this pattern when one-half of said work has been finished.

Similar letters indicate corresponding parts.

In these drawings, the letter A designates a frame, into which is fitted the carriage B, so that said carriage can be moved up and down. Various means may be used for imparting to

the carriage this up-and-down movement—such as a rack and pinion or suitable levers. In the example represented by the drawings I have shown a spindle, C, which has its bearings in the head D, and on which is mounted a drum, E, from which extends a rope, cord, or chain, a , to the carriage B. From this carriage extends another rope, cord, or chain, b , over one or more pulleys, c , and to the free end of this rope is secured a weight, e . This weight slightly overbalances the weight of the carriage with all the parts connected to it, and when the spindle C is turned so as to wind up the rope a on the drum E, the carriage is depressed; but if the spindle is turned in the opposite direction the carriage is raised by the action of the weight. The spindle C is turned by a treadle, which connects by a belt with a pulley, f , mounted on the spindle, (the belt and treadle being not shown in the drawings.)

On the carriage B are mounted the work-support F and the pattern-slide G. In the example shown in the drawings the work-support is secured to a slide, H, which is fitted into guideways extending transversely across the carriage; but if it is desired to reproduce on the work only rectilinear designs, the work-support may be rigidly secured to the carriage. The pattern-slide G fits into guideways g , formed in the carriage or in a casting firmly secured to said carriage, and a screw-spindle, I, serves to impart to said pattern-slide a movement transversely to the carriage or in a direction at right angles to the rising and falling movement of said carriage.

On the pattern-slide is firmly secured the pattern J, on the face of which is engraved, etched, or otherwise produced a counterpart of the design which is to be reproduced on the face of the work—that is to say, if the work is to be ornamented by diamonds produced by right lines of gradually increasing and decreasing length, leaving diamond-shaped blank spaces between them, as indicated in Fig. 5, the pattern consists of diamonds which are alternately raised and depressed, and when the tracer moves over one of the depressed panels or sections of the pattern, the graver produces the lines on the work, while, when the tracer moves over one of the raised

panels or sections of the pattern, the graver is pushed away from the work, as will be presently more fully explained.

The tracer *h* is secured in an arm, *K*, which is hinged to the tracer-slide *L*, so that when the tracer is moved over the face of the pattern, it can fall into the depressed panels or recede, so as to move over the raised panels of the pattern. The tracer-slide *L* moves up and down in guideways *i*, Fig. 3, formed in a standard, *M*, which is firmly secured to the base supporting the frame *A*, and it connects by the rod *N*, lever *O*, and link *P* with the carriage *B*. The lever *O* has its fulcrum on a pivot, *j*, which can be adjusted in a slot, *k*, so that by moving the carriage *B* up and down more or less motion is imparted to the tracer-slide *L*. If the fulcrum *j* is adjusted directly in the middle of the lever *O* and the carriage *B* is depressed, the tracer-slide moves up just as much as the carriage moves down; but when the fulcrum *j* is moved toward the outer end of the lever *O*, the movement of the tracer-slide is decreased, and vice versa, and by increasing the movement of the tracer-slide the scale of the design produced on the work is reduced, and vice versa. If it is desired to enlarge the scale of the design produced on the work, the fulcrum *j* of the lever *O* must be placed in an extension of said lever beyond its connection with the rod *N*.

I have termed the rod *N*, lever *O*, link *P*, and the adjustable fulcrum *j* of the lever *O* the pantograph connection between the carriage and the tracer-slide.

The arm *K*, which carries the tracer *h*, bears upon a pin, *l*, which is secured in an arm, *m*, projecting from the support *Q* of the graver *n*. The support is of well-known construction, and it can be moved toward and from the work in guideways *o*, and also across the work in guideways *p*.

When the operation commences, the tracer is supposed to be opposite one of the depressed panels in the pattern and the tool-support is forced inward by a slight pressure of the hand or otherwise, so that the pin *l* bears upon the arm *K* of the tracer and that the graver bears upon the work. The carriage is then depressed and allowed to rise, and the graver produces the first line on the left-hand side of the work, Fig. 5; then the pattern-slide is moved in the direction of arrow 1, Fig. 1, and the graver is moved in the opposite direction, as indicated by arrow 2, the carriage *B* is again depressed and allowed to rise, and the second line is produced on the work. As the operation progresses the lines produced on the work by the graver become broken, because whenever the tracer passes over one of the raised panels of the pattern, the graver is, by the action of the arm *K* on the pin *l*, forced back out of contact with the work; but for each down-and-up stroke of the carriage the graver is carried up and down over the entire face of the work.

The pin *l*, secured to the arm *m* of the graver-support *Q*, bears against the arm *K*, which carries the tracer *h*, and these devices, or equivalent, constitute what I term a "stop," 70 which, by pushing on the graver-support, retains the graver out of contact with the work when the tracer is opposite to one of the high portions of the pattern.

What I claim as new, and desire to secure by Letters Patent, is—

1. The combination, substantially as hereinbefore described, with the graver-support, of the pattern-slide, the screw-spindle for imparting to this slide the requisite motion, the 80 work-support, the carriage supporting the pattern-slide and the work-support, the tracer-slide, the stop which retains the graver out of contact with the work when the tracer is opposite to one of the high portions of the 85 pattern, and means for imparting to the carriage a reciprocating motion.

2. The combination, substantially as hereinbefore described, with the graver-support, of the pattern-slide, the screw-spindle for imparting to this slide the requisite motion, the 90 work-support, the carriage supporting the pattern-slide and the work-support, the tracer-slide, the stop which retains the graver out of contact with the work when the tracer 95 is opposite to one of the high portions of the pattern, the pantograph connection between the carriage and the tracer-slide, and means for imparting to the carriage a reciprocating motion.

3. The combination, substantially as hereinbefore described, with the graver-support, of the pattern-slide, the screw-spindle for imparting to the slide the requisite motion, the work-support, the carriage supporting the 105 pattern-slide and the work-support, the tracer-slide, the arm hinged to the tracer-slide and carrying the tracer, the pin projecting from the graver-support and bearing on said arm, and means for imparting to the carriage 110 a reciprocating motion.

4. The combination, substantially as hereinbefore described, with the graver-support, of the pattern-slide, the screw-spindle for imparting to the slide the requisite motion, the 115 work-support, the carriage supporting the pattern-slide and the work-support, the tracer-slide, the arm hinged to the tracer-slide and carrying the tracer, the pin projecting from the graver-support and bearing on said 120 arm, the pantograph connection between the carriage and the tracer-slide, and means for imparting to the carriage a reciprocating motion.

In testimony whereof I have hereunto set 125 my hand and seal in the presence of two subscribing witnesses.

ANTON SCHWITTER. [L. S.]
